UNITED STATES PATENT OFFICE

97,192

DESIGN FOR A COLLECTION BOX FOR SALES TAX

William Arthur Honeyman, San Anselmo, Calif.

Application March 1, 1935, Serial No. 55,680

Term of patent 7 years

To all whom it may concern:

Be it known that I, William A. Honeyman, a citizen of the United States, residing at San Anselmo, Marin County, State of California, have invented a new, original, and ornamental Design for a Collection Box for Sales Tax, of which the following is a specification, reference being had to the accompanying drawing, forming part thereof, wherein—

Fig. 1 is a perspective view of a collection box for sales tax, showing my new design.

The opposite side of the design is of substantially the same configuration and appearance as the side shown.

I claim:—

The ornamental design for a collection box for sales tax, as shown and described.

In witness whereof I have signed my name to this specification.

WILLIAM ARTHUR HONEYMAN.
